UNITED STATES PATENT OFFICE.

ULYSSES G. WHITE, OF BOULDER, MONTANA.

PROPELLING AND BALANCING MECHANISM FOR AIR-CRAFT.

1,134,790.

Specification of Letters Patent. Patented Apr. 6, 1915.

Application filed March 25, 1912. Serial No. 827,165.

To all whom it may concern:

Be it known that I, ULYSSES G. WHITE, a citizen of the United States, residing at Boulder, in the county of Jefferson and State 5 of Montana, have invented new and useful Improvements in Propelling and Balancing Mechanism for Air-Craft, of which the following is a specification.

This invention relates to air craft generally, and particularly to a propelling and balancing system therefor.

The primary object of the invention is to provide propelling mechanism which also serves as the means for balancing and maintaining the equilibrium of the craft.

A ~~horizontal~~ object of the invention is to provide a propelling mechanism in which the propellers are adjustable to different positions for driving the craft ahead, launching and landing the craft in a substantially direct vertical path, and maintaining both longitudinal and lateral stability.

A still further object of the invention is to provide a steering and balancing mechanism 25 which is automatic in action and may be manually controlled for certain actions when desired.

A still further object of the invention is to provide a propelling and balancing mechanism 30 by which the craft may be launched directly from the ground without a running start, landed with ease and facility and at any given rate of descent, efficiently balanced at all times so as to secure steadiness 35 and stability of flight, and also by means of which an automatic banking action of the right degree is obtained in making turns.

With these and other objects in view, the invention consists of the features of construction, combination and arrangement of parts herein fully described and claimed, reference being had to the accompanying drawings in which:—

Figure 1 is a side elevation, partially in 45 longitudinal section, of an airship or flying machine embodying my invention. Fig. 2 is a sectional plan view of the same. Fig. 3 is a sectional front elevation. Fig. 4 is a cross section through the gear casing of one of 50 the propellers. Fig. 5 is a vertical transverse section on line 5—5 of Fig. 1. Fig. 6 is a detail section on line 6—6 of Fig. 5. Figs. 7, 8, 9 and 10 are diagrammatic views 55 illustrating the balancing actions of the propellers.

Referring to the drawings, 1 designates

the main frame of the structure, which is provided with one or more supporting planes or surfaces 1^a, and may be provided with any suitable type of launching and alighting gear (not shown). In practice, a balloon or aerostat, not shown, may also be employed to sustain a portion of the weight of the machine. The supporting plane or planes and aerostat may be employed independently or 60 jointly, according to the character of aerial vessel it is desired to produce. The craft may also be provided with any suitable type of steering mechanism, such as vertical and horizontal rudders, with suitable means for 65 controlling the same. I have not deemed it necessary to illustrate or describe any of these features in detail, as the present invention relates particularly to a novel and improved type of propelling and balancing 70 mechanism which may be used in connection with aircraft generally.

Mounted on the main frame is a longitudinally extending shaft or axle 2, having lateral rocking motion on its own axis, and 75 suitably journaled and supported upon said shaft 2 is a horizontal transverse shaft 3, the ends of which project beyond opposite sides of the shaft 2. The shaft 3 is thus mounted to rock in a fore-and-aft direction 80 on its own axis independently of the shaft 2, and to rock in a lateral direction with said shaft 2. Supported by and depending from the shaft 3 is a car or platform 4, designed 85 to support the aviator's seat, passengers' seats, if any, and other elements of the load weight of the machine. This car operates, with its load, as a weighted pendulum normally maintained by gravity in a perpendicular position. The described connections 90 between the main frame 1 and the car 4 adapt these elements to have relative lateral and longitudinal motions on the shafts 2 and 3 as axes, in the tilting of the body of the craft out of a balanced position. For convenience of description and setting forth the 95 novel relative motions of the parts, the main frame and elements carried thereby may be termed a body or gliding structure and the car 4 a gravity controlled pendulum.

Arranged at the front and rear of the gliding structure are transverse transmission shafts 5 and 6 which support and transfer motion to front and rear pairs of propellers 7 and 8, the propellers of each pair 100 being arranged on opposite sides of the longitudinal center of the machine. Each

propeller is carried by a shaft 9 journaled in a gear casing 10 carried by a sleeve 11 loosely mounted on the coaxing transmission shaft. The shafts 9 carry beveled gears 12 driven by beveled gears 13 on the transmission shafts, and at their inner ends the respective sleeves are provided with spur gears 14. These shafts 5 and 6 are driven by belts or chains 15 and 16 from one or 10 more motors 17 mounted upon the base portion of the gliding structure, and in turn said shafts 5 and 6 communicate motion to the propellers. The construction and arrangement of the gearing is such, preferably, that the front propellers rotate in an inward direction or toward each other, while the rear propellers 8 rotate in an outward direction or away from each other. The gear casings 10 carry counterweights 10' to 20 accurately balance the propellers. The respective propellers are adapted, through the rotation of the sleeves 11, to be adjusted each through an arc of about 180°, and said propellers have a variety of relative adjusting 25 motions for propelling and balancing actions, as hereinafter fully described. As shown, the gears 14 of the front propellers mesh with rack segments 17 and the corresponding gears of the rear propellers with 30 rack segments 18. The sets of rack segments are pivoted for vertical motion upon the main frame, and the front rack segments 17 have rearwardly extending arms 19 coupled by links 20 to crank arms 21 on the sections 35 of a divided horizontal transverse rock shaft 22, which rock shaft sections are provided with crank arms 23 coupled by links 24 to a connecting head or cross bar 25 carried by the normally horizontal arm of a bell crank 40 lever 26, fulcrumed upon the forward end of the shaft 2. The segments 18 meshing with the gears 14 of the rear propellers are in like manner provided with arms 19' connected by links 20' with the crank arms 21' 45 of rock shaft sections 22' having crank arms 23' connected by links 24' with the ends of a cross head or bar 25' carried by the normally horizontal arm of a bell crank lever 26' fulcrumed to the rear end of the shaft 2. 50 The connections between the gear segments 17 and 18 of the front and rear pairs of propellers are, therefore, the same in construction and arrangement except that the crank arms 23' and coaxing parts are so 55 disposed as to cause the two sets of gearing to adjust the front and rear sets of propellers in opposite directions when the sets of gearing are coupled for adjustment in unison and the vertical arms of the bell 60 crank levers are moved in the same direction.

As shown, the vertical arms of the bell crank levers 26 and 26' are pivotally connected to the front and rear ends of an actuating bar or rod composed of two sections

27 and 27', which sections of the divided bar or rod are pivotally coupled at their relatively inner ends to the sections 28 and 28' of a divided controlling lever. The said lever sections are arranged vertically in 70 transverse alignment and their lower or handle ends are arranged in proximity to the aviator's seat 29 upon the car or platform 4, so that both levers may be grasped and simultaneously moved in the same direction, or the lever section 28 grasped and moved to transmit motion in the opposite direction to the lever section 28'.

The lever sections 28 and 28' are fulcrumed at their upper ends for fore-and-aft swinging motions upon a cross pin 30 extending transversely through and journaled in the shaft 2, and said upper ends of the lever sections carry gear segments or racks 31 and 32 which have beveled faces 80 and mesh with a beveled intermediate gear 33 journaled loosely upon a stud 34 carried by a yoke 35 fixed to the cross pin 30. The sections of the divided lever are thus pivotally supported from the shaft 2, which is 90 journaled upon the gliding structure, and are movable upon the gliding structure in a fore-and-aft direction with relation to the swinging pendulum or car 4. When the lever sections are simultaneously grasped 95 and together moved forwardly or rearwardly the actuating bar sections 27 and 27' will be moved forwardly or rearwardly therewith, and in a like direction to each other, but when the lever section 28 is moved 100 forwardly or rearwardly independently of the lever section 28' motion in the opposite direction will be imparted to the lever section 28' through the gears 31, 33 and 32, as will be readily understood, causing the 105 actuating bar sections 27 and 27' to simultaneously move in opposite directions, through which variable motions of the lever sections 28 and 28' different adjusting movements may be transmitted to the front 110 and rear sets of propellers 7 and 8 for the purposes hereinafter described.

Fixed to the shaft 3 is a curved rack segment 36 adapted to be engaged by a spring actuated locking dog or pawl 37 on the lever section 28, whereby said lever section 28 may be fixed with relation to the swinging pendulum or platform, the gearing between the two lever sections also serving to hold the lever section 28' locked under such conditions. Upon retracting this dog the lever sections will be free for adjusting movements in the same or opposite directions as previously explained, and the dog is engageable at different points with the teeth of the rack 36 to hold the propellers and gliding structure set at different angles with relation to the perpendicular plane of the swinging car or pendulum. The dog or pawl 37 has sufficient vertical play between 125

the teeth of the rack 36 to permit relative tilting motion between the gliding structure and car on the axes 2 and 3 without liability of casual disconnection of said dog from the 5 rack, to permit the car and levers to swing freely on their respective axes.

For the purpose of clearly explaining the mode of operation of my improved propelling and balancing mechanism, it may be 10 assumed, for purpose of illustration, that in flight the gliding structure travels in a substantially horizontal position, the car or pendulum being maintained in a perpendicular position by the force of gravity, and the 15 propellers arranged to revolve in a vertical plane, the necessary angle of incidence being presented by the supporting surfaces 1^a. It will thus be understood that when the craft is flying horizontally at its normal attitude, 20 the front propellers 7 will act as factors operating to pull or draw the craft ahead, while the rear propellers 8 will produce thrust pressures for driving or pushing action. If, in the course of travel, the machine 25 should tilt downwardly and forwardly beyond a balanced position, it will be evident that the car or pendulum 4 will have relative forward motion and will transmit corresponding motion to the sections 27 and 30 27' of the actuating bar as a unit. As a result of this operation, the horizontal arms of the bell crank levers 26 and 26' will be respectively tilted upwardly and downwardly, and motion will be transmitted therefrom 35 through the sets of gearing to the gears 11 of the sleeves of the respective sets of propellers 7 and 8, whereby the front propellers will be swung upwardly to a certain degree and the rear propellers 8 swung downwardly 40 to a like degree, the front propellers thereby operating to exert a combined elevating and pulling action, while the rear propellers will exert a combined depressing and pushing action, thus resisting any further forward tilting 45 tendency of the gliding structure and returning the same to a normally balanced position, restoring the normally relative relationship between the gliding structure and the car or pendulum. If the machine should 50 tilt in a downward and rearward direction, the car or pendulum 4 will have a relative rearward swinging motion and will thereby move the sections 27 and 27' of the actuating bar rearwardly as a unit, thus adjusting the 55 bell crank levers 26 and 26' in the opposite directions to those previously described and transmitting motion through the sets of gearing between said bell crank levers and the gears 11 of the front and rear propellers 7 and 8, to shift the front propellers downwardly to a certain angle and the rear propellers downwardly to a like angle, whereby the front propellers will be caused to exert a pulling and depressing effect and the rear 60 propellers to exert a driving and elevating 65 effect, by which the rearward tilting motion of the gliding structure will be overcome and said structure returned to a balanced position, the normal relationship between the gliding structure and car or pendulum 70 being thereby restored. When, in the travel of the machine, the gliding structure tilts down laterally at the right hand side, the car or pendulum 4 will move in that direction and in so doing will turn the shaft 2 to 75 the left, as a result of which motion will be transmitted through the links 24 and 24' to adjust the propellers of the front and rear sets to like degrees in opposite directions, the right hand front and rear propellers 7 and 80 8 being respectively tilted upwardly and downwardly to exert a propelling and lifting effect, while the left hand front and rear propellers will be respectively tilted downwardly and upwardly to exert a propelling 85 and depressing effect, by which the machine will be restored to a balanced position. If, on the other hand, the machine should tilt downward laterally to the left, the car or pendulum will be moved in that direction 90 and as a result the shaft 2 will be rocked in the opposite direction to that previously described, causing the sets of links 24 and 24' to tilt the left hand front and rear propellers upwardly and downwardly for a propelling and lifting effect, and to tilt the front and rear right hand propellers downwardly and upwardly for a propelling and depressing effect, whereby the balance of the machine will be restored. It will thus be 95 understood that in the travel of the machine any deflection of the body of the machine from a balanced position in either a fore-and-aft or a lateral direction will be counteracted by the action of the propellers, which 100 will be automatically adjusted to maintain the balance of the craft and insure a reliable and efficient degree of steadiness of travel and stability, while the propellers continue to maintain a driving action to support the 105 machine in flight. This result, it will be apparent, is gained by the employment of a simple type of mechanism which adapts the propellers to perform the functions described, whereby the use of balancing devices of the kinds commonly employed may 110 be avoided. In making a turn to the right or left, it will be evident that through the motion of the weighted car or pendulum the propellers will be automatically adjusted to 115 bank the machine to the required degree and to prevent any list beyond the necessary degree for a proper banking action. If desired, the usual vertical and horizontal rudders may be employed and means provided 120 for locking the car or pendulum to the gliding structure against relative motion, so that in the event of accidental derangement of the parts of the propelling and balancing mechanism, which is not liable to occur, the 125 130

machine may be controlled and steered to effect a safe landing.

With the construction described the propellers may be adjusted either upward or downward to an angle of 90° from their normal horizontal positions, and consequently have a total range of adjustment through an arc of 180° . It will be evident that the aviator may at any time release the dog 37 to permit the adjustment of the divided lever. When both lever sections 28 and 28' are moved forwardly, and the actuating bar sections 27 and 27' are moved thereby forwardly as a unit, it will be evident that both the front and rear propellers will be tilted upwardly to degrees according to the extent of forward motion of the lever. The front propellers will thus be adjusted to exert a lifting action and the rear propellers a depressing action, so that the gliding structure may be held and sustained in a climbing attitude while the car or pendulum maintains a normal position, so that the craft may ascend at an angle while it is being propelled forwardly. By adjusting the two sections of the lever rearwardly the actuating bar sections 27 and 27' will be moved rearwardly as a unit, thereby tilting both the front and rear propellers downwardly, so that the front set of propellers will exert a depressing action and the rear set of propellers a lifting action, whereby the gliding structure will be disposed at a descending angle for gliding descent and maintained in such position against the action of the weighted car or pendulum. The adjustments above described may be varied by moving the lever section 28 forwardly or rearwardly, in which motions of the said lever section 28 the other lever section 28' will be caused through the intervening gearing to move in a reverse direction to the lever section 28. In such adjustments of the lever sections it will also be evident that the actuating bar sections 27 and 27' will be moved in opposite directions relatively to each other. When, for instance, the lever section 28 is moved forwardly to its full extent, the front propellers 7 will be tilted upwardly to a substantially horizontal position, and the rear propellers 8 downwardly to a substantially horizontal position, in which operation the propellers will give direct upward lifting thrust, whereby the machine may be launched directly from the ground or caused to ascend in a straight path. With the propellers in such positions, the machine may also be caused to hover over any certain point while it is supported in the air or caused to descend at any desired speed, the rate of speed being governed by regulating the speed of the propellers. On the other hand, when the lever section 28 is moved rearwardly to its full extent the front propeller 7 will be tilted

downwardly and the rear propellers 8 upwardly, so that both sets of propellers will exert a depressing action, allowing a rapid descent to be made to avoid collisions, etc. By varying the degrees of forward or rearward movement of the lever section 28 it will be obvious that the propellers may be manually adjusted and controlled for longitudinal balancing actions. Also by moving the lever laterally the shaft 2 may be rocked in either direction to manually effect adjustments of the propellers in the manner previously described for lateral balancing control.

It will be apparent from the foregoing description that my invention provides a propelling mechanism which is not only of maximum efficiency for propelling purposes, but which also serves as a balancing mechanism, which may be automatically or manually controlled, and which when automatically controlled will give a sensitiveness of action to maintain steadiness of motion of the craft in flight. By providing means for manually adjusting the propellers provision is made for rendering the automatic adjusting means inoperative whenever desired, so as to give the aviator complete control over the machine. The principle employed may be used in air craft of either the heavier or lighter than air type, or any craft which combine the principles of the aeroplane and aerostat, the invention not being limited in these particulars.

I claim:—

1. In a combined propelling and stabilizing mechanism for aircraft, the combination of a body structure, propellers at the front and rear of the body structure, said propellers being arranged on opposite sides of the longitudinal center of the body structure and mounted to tilt in a vertical plane, a longitudinally and laterally movable gravity controlled element, and adjusting means controlled by said element in its longitudinal movements to adjust the propellers of one set in one direction and the propellers of the other set in the opposite direction, said adjusting means being controlled by the lateral movements of said gravity controlled element to adjust the propellers of each set in dissimilar directions.

2. In an aircraft, the combination of a body structure, a shaft extending longitudinally of and mounted to rock in a direction transversely of the body structure, a car mounted upon said shaft for longitudinal swinging movements, sets of transversely alined propellers at the front and rear of the body structure and on opposite sides of the longitudinal center thereof, said propellers being mounted to tilt vertically, sets of adjusting devices for independently controlling the respective propellers, means operated by the lateral movements of the

shaft for controlling the adjusting connections to tilt the propellers of each set in opposite directions and the propellers on each side of the longitudinal center of the machine in like directions, and means controlled by the longitudinal swinging movements of the car for controlling the adjusting connections to tilt the propellers of each set in the same direction and the propellers 10 of the two sets in opposite directions.

3. In an aircraft, the combination of a body structure, a shaft extending longitudinally of and mounted to rock in a direction transversely of the body structure, a gravity controlled car pivoted to swing laterally upon the shaft, propellers located at the front and rear of the body structure and on opposite sides of the longitudinal center thereof, said propellers being mounted to 15 tilt vertically, a set of adjusting connections for each propeller, means whereby under the rock movements of the shaft the sets of connections will be actuated to tilt the propellers of each set in opposite directions and 20 the propellers of the sets at opposite sides of the body in like directions, and a longitudinally movable member operable by the car for operating the sets of adjusting connections to tilt the propellers of each set in the 25 same direction and to tilt one set of propellers in one direction and the other set of propellers in the reverse direction.

4. In an aircraft, the combination of a body structure, a shaft extending longitudinally of and mounted to rock in a direction transversely of the body structure, a gravity controlled car pivotally mounted to swing longitudinally from said shaft, sets of propellers at the front and rear of the machine 30 on opposite sides of the longitudinal center thereof, said propellers being mounted to tilt vertically, a set of adjustable connections for each propeller, connecting means between the shaft and the adjusting connections at each end of the body for adjusting the propellers at each end simultaneously in opposite directions and adjusting the propellers at opposite ends and at the same side of the body in the same direction, and a longitudinally movable member operable by the 35 car for controlling the said connecting means for imparting motion to the adjusting means to adjust the propellers of each set simultaneously in the same direction and to adjust 40 the propellers of the different sets in opposite directions.

5. In an aircraft, the combination of a body structure, a shaft extending longitudinally of and mounted to rock in a direction transversely of the body structure, a gravity controlled car supported to swing longitudinally from the shaft, sets of propellers at the front and rear of the body structure and on opposite sides of the longitudinal center 45 thereof, a set of adjusting connections for

each propeller, and connecting means between the adjusting connections of each set of propellers and the shaft whereby in the 50 rocking motions of the shaft the propellers of each set will be adjusted in opposite directions and the propellers at each side of the longitudinal center of the machine in the same direction, a longitudinally movable member coupled to the said connecting means and adapted to be adjusted by the 55 longitudinal movements of the car to adjust the propellers of each set in the same directions and the propellers of the two sets in opposite directions, and a connecting means between the car and said longitudinally movable member and adjustable to set 60 said longitudinally movable member at different predetermined positions.

6. In an aircraft, the combination of a body structure, a longitudinally movable shaft mounted to rock in a direction transversely of the body structure, a gravity controlled car supported from the shaft to swing laterally therewith and longitudinally independently thereof, front and rear sets of propellers mounted to tilt vertically, the propellers of each set being arranged on opposite sides of the longitudinal center of the machine of the body, a set of adjusting connections for each propeller, vertically adjustable members connecting the sets of adjusting devices at each end of the body with the respective ends of the shaft, said connecting devices being adapted to impart dissimilar adjustments to the propellers of each set on the rocking movements of the shaft, a coupling connection between said connecting devices movable under the longitudinal movements of the car to adjust said connecting devices to transfer motion to each set of adjusting devices to adjust the propellers of each set in the same direction and to adjust the propellers of the two sets in opposite directions.

7. In an aircraft, the combination of a body structure, a shaft extending longitudinally of and adapted to rock in a direction transversely of the body structure, a gravity controlled car supported to swing laterally with the shaft and longitudinally independently of the shaft, right and left hand propellers at the front and rear of the machine, adjusting connections for each propeller for tilting the same in a vertical plane, coupling means connecting each set of adjusting connections with the adjacent end of the shaft, whereby to impart dissimilar movements to the propellers of each set in the rocking motions of the shaft, a longitudinally movable element coupling said coupling connections and movable longitudinally in the swinging movements of the car for adjusting said coupling connections to tilt the propellers at each end of the body in the same direction and the propellers at the opposite ends 110

of the body in reverse directions, and a coupling connection between the car and longitudinally movable member, said coupling connection being pivotally supported by the 5 longitudinal shaft and having an adjustable engagement with the swinging car.

8. In an aircraft, the combination of a body structure, a shaft extending longitudinally of and mounted to rock in a direction 10 transversely of the body structure, a gravity controlled car supported to swing laterally with the shaft and longitudinally independently thereof, front and rear right and left hand propellers mounted to tilt 15 vertically, a set of adjusting devices for each propeller, connecting means between the front and rear sets of adjusting devices at the opposite ends of the shaft, said connecting means being vertically movable and 20 mounted to rock laterally with the shaft, a longitudinally movable element coupling the connecting means at the opposite ends of the shaft for movement in unison, and a pivotally adjustable connection between the 25 said longitudinally movable member and the swinging car.

9. In an aircraft, the combination of a body structure, a shaft extending longitudinally thereof and mounted to rock in a direction 30 transversely thereto, a gravity controlled car pivotally supported to swing laterally with the shaft and longitudinally independently thereof, right and left hand propellers at the front and rear of the machine, vertically 35 movable sets of adjusting connections for each propeller, levers at the ends of the shaft provided with cross pieces coupling the adjacent sets of adjusting devices, a longitudinally movable member connecting the 40 said levers for imparting vertical motion thereto, said member being composed of divided sections, a lever composed of di-

vided sections connected with the sections of the longitudinally movable member, said lever sections being in gear with each other 45 and pivotally supported by the shaft, and an adjustable locking connection between the car and one of said lever sections.

10. In an aircraft, the combination of a body structure, a shaft extending longitudinally of and mounted to rock in a direction 50 transversely of the body structure, a gravity controlled car pivotally supported for lateral motion with the shaft and for longitudinal motion independently thereof, right 55 and left hand propellers at the front and rear of the machine, said propellers being pivotally supported for adjustment in a vertical plane, a set of connections including a rock shaft for tilting each propeller, 60 vertically movable levers at the ends of the shaft, connections between each lever at the adjacent rock shafts for actuating said shafts to adjust the propellers of each set 65 in dissimilar directions on the rocking motions of the longitudinally extending shaft, a longitudinally movable sectional bar having its sections connected with said levers, a divided manually operable lever pivotally supported upon the longitudinally extending 70 shaft, said lever sections being in gear for reverse movements in unison and respectively connected with the sections of the bar, a locking device carried by one of said lever sections, and a locking element associated 75 with the swinging car adapted for adjustable locking engagement with said locking device.

In testimony whereof I affix my signature in presence of two witnesses.

ULYSSES G. WHITE.
